PIPE WRENCH

Filed June 13, 1928

UNITED STATES PATENT OFFICE

GIUSEPPE DELUCA, OF RAYLAND, OHIO

PIPE WRENCH

Application filed June 13, 1928. Serial No. 284,945.

This invention relates to improvements in pipe wrenches, and the primary object of the invention is to provide a wrench of this kind which will have a firm gripping action upon the pipe without tending to mutilate or crush the same.

Another object of the present invention is to provide a pipe wrench which is extremely simple and durable in construction, efficient in operation, and adapted to be applied to a pipe and locked thereon with a minimum expenditure of time and labor.

The invention consists in the novel form, combination and arrangement of parts hereinafter more fully described, shown in the accompanying drawing and claimed.

In the drawings:

Figure 1 is a side elevational view of a wrench embodying the present invention, with the jaws in released position.

Figure 2 is a similar view with the jaws in clamping position and applied to a pipe; and

Figure 3 is an edge elevational view looking toward the right of Figure 1.

Referring more in detail to the drawing, the present wrench embodies an elongated handle 8 whose outer end is bifurcated to provide a pair of spaced legs 9 having a pair of transversely aligned openings inwardly of the free ends thereof to receive a pin 10 forming a pivotal and sliding attachment for a segmental inner jaw 11 by loosely passing through a longitudinal elongated slot 12, provided in the shank 13 of said jaw 11. The shank 13, which is straight, is provided on the inner end of the jaw 11 and slidably extends between the legs 9 at an oblique angle to the longitudinal axis of the handle 8 as clearly shown in the drawing. The jaw 11 is pivoted at its outer end by means of a pin 14 to a second segmental jaw 15 whose inner end is detachably pivoted between the outer ends of the legs 9 by means of a removable pivot pin 16 which passes through transversely aligned openings in the outer ends of the legs 9 and through an opening in the inner end of the jaw 15. The pin 16 may be retained in place by any suitable means such as a cotter pin 17 passing through

a transverse opening in the shank of said pin 16 as shown.

The inner faces of the jaws are formed with transverse teeth or serrations 18, so that when the jaws are drawn together against the pipe, a firm grip will be had upon the latter without danger of the pipe turning within the jaws. It is particularly noted that the inner end of the slot 12 is substantially the same distance from the pivotal connection 14 between the jaws as the pivot 16 is from the said pivotal connection 14. Thus, when the handle 8 is swung from the position of Figure 1 toward the left to the position of Figure 2, the pin 10 will move away from the pivotal connection 14 and have a camming action on the outer wall of the slot 12 so as to swing the jaw 11 toward the jaw 15 and thereby cause the jaws to grip the pipe with a force proportional to the force applied to the handle. Naturally, in this operation, the handle 8 swings about the removable pivot pin 16 to obtain the handle lever grip described.

In use, the pin 16 is removed and the outer jaw 15 is swung outwardly on the pivot 14 to open position. The jaw 11 is then engaged with the pipe and the jaw 15 is again closed against the opposite side of the pipe, whereupon the pivot pin 16 is replaced with the parts disposed as in Figure 1. The handle 8 is then swung to the left for gripping the pipe securely as illustrated in Figure 2.

It will be noted that the jaws 11 and 15 are of substantially semi-circular form and are adapted to grip the pipe substantially evenly entirely about the circumference of the latter, thereby enabling a firm grip to be had upon the pipe without danger of crushing the latter under ordinary conditions of use. Moreover, the construction is extremely simple and durable, avoiding the use of unreliable and objectionable latching members although permitting ready application of the wrench to the pipe and providing for securely maintaining the wrench on the pipe when once applied.

Minor changes may be made without departing from the spirit and scope of the invention as claimed.

What I claim as new is:

In a pipe wrench, a handle, complementary inner and outer jaws pivotally connected together at their outer ends, each of said jaws being formed at its inner end with a straight shank substantially parallel to each other, and approximately perpendicular to the handle, the shank of the inner jaw being formed with a longitudinally disposed slot, 5 said handle being pivoted at one end to the inner end portion of the shank carried by the outer jaw, and a pin carried by the pivoted end portion of the handle for cooperation with the aforementioned slot.

10 15 In testimony whereof I affix my signature.
GIUSEPPE DELUCA.
